UNITED STATES PATENT OFFICE.

GEORGE W. MULLER, OF WASHINGTON, DISTRICT OF COLUMBIA.

RAILWAY-RAIL JOINT.

Application filed November 21, 1925. Serial No. 70,520.

To all whom it may concern:

Be it known that I, GEORGE W. MULLER, a citizen of the United States, residing at Washington, in the District of Columbia, have invented certain new and useful Improvements in Railway-Rail Joints, of which the following is a specification.

This invention relates to railway rail supports, and has for one of its objects to increase the strength of joint or the coupling means between the ends of the rails, to effectually resist the tendency to the deflection of the rails at the point of juncture under the severe pounding of the rolling stock.

15 The improved device may be adapted to rails of various sizes and weight without material structural change in the rails, or reducing the strength.

The ordinary railway rails are usually united end to end by clamping devices which lap over the confronting portions of the rails at opposite sides and bear beneath the ball or tread and against the opposite sides of the web at some distance from the 25 ends of the rails.

The clamp devices thus constructed bear substantially the entire length against the under face of the ball and upon the upper face of the tie flange.

30 Experiment and observation have shown that when trains pass over the rails the pounding of the wheels of the train, especially the very heavy locomotives now in use, has a tendency to deflect the confronting ends of the rails, and when the rail ends are secured by clamp plates of the ordinary construction in contact their whole lengths against both the ball and the tie flanges, and rigidly connected to the webs of the rail by 35 a plurality of relatively heavy clamp bolts, the outer portions of the clamp plates are correspondingly humped up or elevated, and while this depression and elevation may not be evident to the eye of an observer, it is 40 sufficient to cause a very perceptible unevenness of motion to the train.

The clamp plates as ordinarily constructed are of uniform thickness and width throughout, and when depressed or bent down opposite the rail ends, they remain in bent down 45 position, especially if the depression is suf-

ficient to destroy the elasticity of the metal.

When a train approaches a joint distorted as above described, the first hump or elevation in the rail causes a slight uphill movement and then down hill toward the meeting ends of the rails and then uphill again and over the second hump or elevation, and this operation being repeated by each wheel in passing aggravates the abnormal condition, and requires constant care and readjustment, and the replacing of the impaired plates, which is a source of relatively heavy expense.

55 The plates in common use are relatively heavy, but the weight is not properly distributed to secure the best results, and one of the objects of the present invention is to so construct the clamp plates as to properly distribute the material by increasing the 60 weight and thickness where the greatest strains occur and without materially increasing the weight as a whole.

65 Another object of the invention is the employment of a support having an upwardly directed intermediate portion so arranged as to receive the impact of the wheels as they 70 pass over the rails and operative to prevent the distortion of the balls of the rails at their confronting ends.

75 To this end the invention consists in the construction of plates which bear at a medial point beneath the balls of the rails at their meeting points, and not bearing at this 80 medial point upon the tie flanges, and bearing at the terminals upon the tie flanges but not in contact with the balls or treads, and likewise formed with an upwardly directed medial portion conforming to the ball portions of the rails at their confronting ends.

85 By this means a truss like construction is produced, and the clamp bolts so located as to supplement the arch or truss like construction and materially increase the efficiency 90 and utility thereof.

95 In the drawings illustrative of approved forms of the construction and in which like reference characters are employed for like parts in all the views, —

Figure 1 is a side elevation from the outer 100 side.

Figure 2 is a plan view with one of the

rails in section on the line 2—2 of Figure 1.

Figure 3 is a transverse section on the line 3—3 of Figure 1.

Figure 4 is a transverse section on the line 5 4—4 of Figure 6.

Figure 5 is a transverse section on the line 5—5 of Figure 6.

Figure 6 is a side elevation from the inner side.

10 Figure 7 is a detail of portions of the confronting ends of the rails.

The improved devices may be applied to rails of various sizes, but for the purpose of illustration are shown applied to the confronting ends of standard forms of rails including heads or treads 10, webs 11 and tie flanges 12.

15 The improved plate is formed of a body portion 13 increased in thickness intermediate the ends as shown at 14 and with a laterally directed enlargement 15 arranged to bridge over the confronting ends of the rails, as shown.

20 Reinforcing ribs 16 are preferably formed on the outer face of the body portion 13 and merge at the ends into the body and also into the thickened portion 14 and the enlargement 15.

Near their ends the body portions 13 are 25 formed with lateral projections 17 which bear upon the upper faces of the tie flanges 12, as shown more clearly in Figures 4 and 5.

30 The body portion 13 is reduced in vertical width toward the ends, as shown in Figures 1 and 6.

35 Recesses 18 are formed in the ball portions 10 of the rails at one side at their confronting ends, the recesses corresponding 40 in depth to the portion of the balls at one side of the web 11, the web portions not being reduced in any manner by the forming of the recesses. The recesses are formed in the outer portions only of the balls, and the 45 enlarged portion 15 of the plate 13 for the outer side of the rail is formed with a lateral enlargement 19 corresponding to the recesses and engaging in the same as shown in Figures 1 and 2.

50 The confronting ends of the rails are spaced to provide for the expansion of the rails in warm weather, and the extension 19 is shorter than the recesses, for the same purpose, as shown.

55 The upper face of the projection 19 conforms to the upper faces of the balls 10, so that the wheels of the rolling stock will pass smoothly over the joint and without producing jars or concussions.

60 By this arrangement, it will be observed, the plates bear by their thickened and reinforced medial portion against the under face of the head portions 10 of the rails, but are spaced from the tie flanges below the 65 enlargement, as shown in Figure 3, and bear

at the ends by the projections 17 upon the tie flanges 12, but do not engage the balls of the rails at the terminals of the plates, as shown in Figure 5.

The reinforcing ribs 16 are arranged 70 reversely oblique to the longitudinal axis of the plates, and thus coat with the medial enlargement to accentuate the truss like form of the plate.

The recess engaging extension 19 coats 75 with the enlargement 13 to materially increase the efficiency of the supporting devices.

Clamp bolts 20 extend through the plates and the webs of the rails, and firmly bind 80 the parts together, the apertures for the bolts in the webs of the rails being elongated in the usual manner to provide for expansion and contraction, and materially increase the strength of the joint, and provide 85 an effectual holding means where the greatest lateral strain occurs.

A clamp bolt 21 extends through the enlargements 14, the ends of the webs of the rails being formed with cut out portions 14^a 90 to receive the bolt. This central bolt 21 is employed in addition to the other clamp bolts, and adds greatly to the strength of the joint besides providing effectual holding means where the greatest lateral strain 95 occurs.

The clamp bolts 20 near the ends of the plates are disposed at a lower point than the other bolts, with the centre lines of the bolts in alignment with the centre lines of the adjacent bolts and the upper ends of the enlargements 14, to complete the trussing arrangement.

100 By this arrangement it will be noted, the medial portion 19 of the outside plate is flush with the upper faces of the balls 10 of the rails at their confronting ends so that the wheels run over the joint in direct contact with the clamp plate as well as on the rails thereby effectually preventing the deflection 110 of the rails at the ends.

Again, with such an arrangement, the outside clamp plate is also of the full height of the rail and thus materially stiffens the rail at the point of the greatest downward stress and deflection to effectually resist any tendency to displacement.

115 The central portions of the clamp plates by being thicker than the outer portions, thereby provide the necessary reinforcement at the point where the greatest strains occur.

The plates are gradually decreased in thickness toward the ends, and are spaced a short distance from the webs 11, the spacing gradually increasing toward the ends as shown at 22 in Figure 2. The spacing is also increased slightly from the upper toward the lower edge as shown in Figures 4 and 5.

120 By this means when force is applied to 130

the terminal clamp bolts, the medial thicker portions 13 of the plates are forced up under the balls of the rails, and the extension 19 being flush with the upper surfaces of the balls, thus prevents sagging or depression at this point where support is most needed.

The balls at the ends of the rails are caused to flow to some extent under the 10 severe pressure and hammer blows of the heavy rolling stock and this displacement is usually in the outer portions of the balls only as the flanges of the wheels wear away said displaced material at the inner faces 15 of the balls. By forming the central portion of the outer clamp plate with the extension 19 flush with the balls of the rails, and to be held rigidly in place by the upper bolt 20, the rail ends are effectually supported and prevented from flowing or 20 from lateral displacement.

From the foregoing it will be gathered that the web of the rail is hugged by each side of the mid-portion of the clamp plates, but 25 a slight clearance exists between the web and each side of the terminals of said clamp plates, said graduated space or clearance sloping gradually between the inner side of the plates and web to where the centre 30 connects with the web. This is an important feature and materially adds to the utility, strength and efficiency of the invention as a whole.

What is claimed and desired to be secured by Letters Patent is:—

1. A clamp plate formed with the terminal portions to bear upon the flanges of the rails and spaced from the ball and the intermediate portion bearing beneath the 40 balls of the rails and spaced from the flanges thereof, said intermediate portion having an extension flush with the upper faces of the balls.

2. A clamp plate formed with terminal 45 portions to bear upon the flanges of the rails and spaced from the balls thereof, said plate also spaced toward the ends from the rail webs, and the intermediate portion of said plate bearing beneath the balls of the 50 rails and spaced from the flanges thereof, said intermediate portion having an extension flush with the upper faces of the balls.

3. A clamp plate formed with an intermediate portion to bear beneath the ball 55 of a rail and having an extension flush with the upper face of the ball, and terminal portions spaced from the web of the rail and arranged to bear upon the 60 flanges of the rail.

4. A clamp plate formed with an intermediate portion of increased thickness to 65 bear beneath the ball portions of the rails, and having an extension flush with the upper faces of said ball portions, and ter-

minal portions spaced from the web of the rail and arranged to bear upon the flanges of the rails.

5. A clamp plate formed with an intermediate portion to bear beneath the ball 70 portions of aligned rails, and having an extension flush with the upper faces of said ball portions, and with lateral extensions at the terminals of the plates to bear upon the flanges of the rails. 75

6. Clamp plates each formed with an intermediate portion to bear beneath the balls of aligned rails, one of said plates having an extension flush with the upper faces of said balls, both of said plates having terminal portions to bear upon the flanges of the rails, and means operative to bind the plates against the webs of the rails. 80

7. Clamp plates each formed with an intermediate portion of increased thickness 85 to bear beneath the ball portions of aligned rails and with terminal portions to bear upon the flanges of the rails, one of said plates having an extension flush with the upper faces of the ball portions, and means 90 operative to bind the plates against the webs of the rails.

8. A clamp plate formed with an intermediate portion to bear beneath the balls of rails, and having an extension flush with 95 the upper faces of the balls, and terminal portions to bear upon the flanges of the rails, and reinforcing ribs directed reversely oblique to the longitudinal axis of the plate and operative to produce truss like supports 100 to the plate.

9. A clamp plate formed with an intermediate portion of increased thickness to bear beneath the balls of rails, and having an extension flush with the upper faces of the balls, and with terminal portions to bear upon the flanges of the rail, and reinforcing ribs directed reversely oblique to the longitudinal axis of the plate and merging into the thickened portion thereof. 110

10. A clamp plate formed with an intermediate portion of increased thickness to bear beneath the balls of rails, and having an extension flush with the upper faces of the balls, clamp bolts operating through the 115 terminal portions of the plates, and the webs of the rails, and clamp bolts operating through the plates and the webs of the rails and spaced from the terminal bolts and in alignment with the same and the ball engaging portions.

11. Clamp plates each formed with an intermediate portion to bear beneath the balls of rails and having an extension flush with the upper faces of the balls, and spaced from the flanges of the rails and with terminal portions to bear upon the flanges of the rails; clamp bolts operating through the terminal portions of the plates and the webs of the rails, and clamp bolts operating through the 120 125 130 rails, and clamp bolts operating through the

plates and the webs of the rails and spaced from the terminal bolts and in alignment with the same and the ball engaging portions.

- 5 12. Clamp plates each formed with an intermediate portion to bear beneath the balls of aligned rails and having an extension flush with the upper faces of the balls and spaced from the flanges of the same and with
- 10 terminal portions to bear upon the flanges of the rails, and a clamp bolt operating through the plates and in relatively close proximity to the ball portions.
- 15 13. Clamp plates each formed with an intermediate portion to bear beneath the balls of aligned rails, and having an extension flush with the upper faces of the balls, and spaced from the flanges of the same and with terminal portions to bear upon the flanges of

the rails, the confronting end of said rails 20 having aligned recesses relatively close to the balls, and a clamp bolt operating through the plates and received in said recesses.

14. In a railway rail joint, the combination with aligned meeting rails having recesses formed in the outer portions of the balls thereof, of clamping plates each formed with portions to bear beneath the balls of aligned rails, one of the said plates having an extension occupying the said recesses, the said extension being constructed and arranged flush with the upper faces of the balls of the rails, the said plates having middle portions spaced from the flanges of the rails, and clamping bolts for securing 30 the said clamping plates and rails together.

In testimony whereof I affix my signature.
GEORGE W. MULLER.
